CLAIM

The ornamental design for a lantern as shown and described.

DESCRIPTION

FIG. 1 is a perspective view of the lantern according to the invention, showing the top, front and side of the lantern.

FIG. 2 is a perspective view of the lantern, showing the bottom, back and side of the lantern.

FIG. 3 is a front plan view of the lantern.

FIG. 4 is a left side plan view of the lantern.

FIG. 5 is a back plan view of the lantern.

FIG. 6 is a right side plan view of the lantern.

FIG. 7 is a top plan view of the lantern; and,

FIG. 8 is a bottom plan view of the lantern.

The broken lines are for the purpose of illustrating the environment of the article only and form no part of the claimed design.
